METHOD AND MACHINE FOR FILLING AND WRAPPING PACKAGES

Roderick W. Hoag, Melrose, Mass., assignor to
 Hoag-Russell Corporation, Melrose, Mass., a
 corporation of Massachusetts

Application August 22, 1952, Serial No. 305,834

5 Claims. (Cl. 53—10)

1

This invention relates to methods and machinery for filling and wrapping articles in general, and more specifically to the manufacture of shaker dispenser packets filled with granular or powdered materials. Such a dispenser packet is described and claimed in United States Patent No. 2,499,313, issued to me February 28, 1950. This present application embodies improvements over Patent No. 2,544,020, issued to me March 6, 1951.

One object of my invention is to provide a method of filling and wrapping webs of packets, at high speed, by a succession of operations.

Another object of my invention is to provide a machine for filling and wrapping webs of packets by a sequence of operations.

With said objects in view, my invention consists in the method and machine for filling and wrapping webs of packets substantially as herein-after described and claimed.

Of the accompanying drawings:

Figure 1 is a plan view of the machine.

Figure 2 is a front view of Figure 1.

Figure 3 is a plan view of a section of the wrapping material with two webs of the packets to be wrapped positioned thereon and secured thereto.

Figure 4 is a section at 4—4 of Figure 3.

Figure 5 is a section at 5—5 of Figure 3.

Figure 6 is a section at 6—6 of Figure 3.

Figure 7 is a partial section at 7—7 of Figure 3.

Similar reference characters indicate similar parts or features in all of the views.

It will aid toward an understanding of the machine, and of the method of filling and wrapping webs of packets, to describe the web of wrapping material, and the webs of packets, and thereafter explain the action of the machine as it operates to produce filled, wrapped packets.

Referring first to Figure 3, there is illustrated a web of paper wrapper material A which usually carries printed matter on the surface that will form the outside surface of the packet wrapper. The first step in my method of filling and wrapping packets consists in longitudinally slitting the wrapper web A at the center B as it is advanced, thus providing two wrapper webs C and D. A web of partly formed corrugated container elements E is positioned on the wrapper web C, and a web of partly formed corrugated container elements F is positioned on the wrapper web D. The margin G of wrapper web C is adhesively treated, and the margin H of web D is adhesively treated. The said margin G of wrap-

2

per web C is folded, pressed and secured against the adjacent margin of the corrugated container elements E, and the margin H of web D is folded, pressed and secured against the adjacent margin of the container elements F. This serves to close one of the two openings of each of the container elements. The packet webs E and F are each longitudinally cut slightly at J and K respectively to provide means for opening the packets for pouring out the contents of the completed packets. The two web assemblies are next turned 90 degrees from a horizontal position to a vertical position to receive the commodity to be packaged in the pockets or corrugations of the webs of packets. The free, upwardly extending margins of wrapper webs C and D are next adhesively treated and then folded, pressed and secured to the adjacent margins of packet webs E and F respectively. The duplex web assemblies are then transversally severed to provide individual packet units.

Referring to Figures 1 and 2 there is schematically illustrated a machine for producing filled packets. The several mechanisms comprising the machine are mounted on a frame 1.

The wrapper web A with two corrugated webs of packets E and F are advanced horizontally to slitting knife 2 secured to shaft 3 journaled in frame 1. Also secured to shaft 3 are two knives 4 and 5 which serve to provide dispensing cuts L and M (Fig. 3) in the crown of each pocket of the webs E and F respectively. A roller 6 journaled in frame 1 serves to support the web A as it is advanced. The webs are next acted upon by an adhesive applying device which serves to apply a strip of adhesive to the top, adjacent margins G and H of webs C and D (Fig. 3) respectively. The adhesive applying device comprises an adhesive containing receptacle 7 secured to frame 1. A bracket 8 is supported by the receptacle 7. Rollers 10 and 11 are coated with adhesive by contact with roller 9 which rotates in liquid adhesive contained in receptacle 7. The said rollers 11 act in the conventional manner to deposit a film of adhesive on the margins G and H of webs C and D.

As the web assemblies advance a pair of folding bars 12 and 13 secured to frame 1 serve to fold the adhesively treated margins G and H of webs C and D over the corresponding margins of the corrugated webs E and F. Rollers 14 secured to shaft 15 journaled in frame 1 act to roll and press flat the folded, adhesively treated margins of webs C and D against the corresponding margins of the corrugated container webs E and F.

The duplex webs are then drawn between two guide rollers 16 each secured to a shaft 17 journaled in frame 1. The web assembly composed of webs D and F is twisted and positioned with the open ends of the pockets of the corrugated web F facing upwardly at an angle of 90 degrees from a horizontal to vertical position and is advanced horizontally with the free flat surface of web D against and guided by vertical roller 18 journaled on shaft 19 secured to frame 1. The web assembly composed of webs C and E is twisted and positioned with the open ends of the flutes of the corrugated pockets of web E facing upwardly at an angle of 90 degrees from a horizontal to vertical position and is advanced horizontally with the free flat surface of web C against guide roller 20 secured to shaft 21 and journaled in frame 1. Both web assemblies are then advanced to pass under a commodity filling hopper 22 secured to bracket 23 mounted on frame 1. Openings 24 are provided in the bottom of the hopper through which the product to be packaged passes downwardly and into the corrugated pockets of the container webs as they pass under the said openings. A receiving bin 25 is positioned under the openings 24 in the hopper 22 to catch the overflow from the corrugated pockets of the webs while the filling operation is being performed. The two composite webs are next advanced from the filling operation and the top margins N and O of webs C and D are then folded at right angles over the flutes of container webs E and F by the action of folding bars 26 and 27 respectively secured to frame 1. Adhesive is then applied to each of the partly folded margins of webs C and D by glue wheels 28 secured to shaft 29 journaled in glue pot 30 mounted on frame 1. The composite webs then advance to pressure rollers 31 and 32 secured to shafts 33 and 34 respectively journaled in frame 1, which serve to fold and firmly press the adhesively treated margins of webs C and D over the open ends of the filled pockets of the container web. The filled composite webs are then advanced to pass against guide rollers 35 and 36 respectively secured to shafts 37 and 38 journaled in frame 1. The composite webs are each twisted back 90 degrees to horizontal position and advanced by feed rollers 39 secured to shafts 40 journaled in frame 1. From the feed rollers 39 the two composite webs of filled, wrapped container elements are advanced to cut-off rollers 41 and 42 secured to shafts 43 and 44 respectively journaled in frame 1. The knife 45 fastened to roller 41 is arranged to cut the traveling composite webs of container elements transversely to provide individual filled packages. From the cut-off rollers 41 and 42 the packages are advanced to a delivery table 46 where they are picked up for use.

It will be understood without need of illustration that any suitable motor may be employed for operating the machine, and that proper gearing is employed in practice to cause the various rolls to rotate at uniform speed to effect travel, control, and fabrication of the web through the machine in order that the operation of the several units thereof will be effected in suitable sequence.

While I have illustrated and described the preferred construction of my machine and the preferred method for carrying out my invention, these are capable of variation and modification, without departing from the spirit of the invention.

It will be obvious to those skilled in the packing art that the web materials may be pre-treated with heat sealing coatings, thus requiring

the substitution of heat sealing and pressure devices for the adhesive applying mechanisms shown in this instant application.

Having described my invention, what I claim is:

- 5 1. The method of making filled wrapped packages by a sequence of operations; consisting in advancing a web of flat, flexible, wrapper material having positioned longitudinally thereon and transversely spaced apart from each other, and inward from the side margins of the wrapper web, two webs of single faced transversely corrugated material with the ends of the corrugations open; severing the web of flat flexible wrapper material to provide two web assemblies, each composed of a web of flat wrapper material with a web of corrugated material positioned thereon; cutting the crown of each corrugation near the margin of the corrugated web to provide a weakened point so that the packages may be easily broken for dispensing the contents; adhesively treating the inner top margins of the flat wrapper material; folding, pressing and securing the inner margin of each web of wrapper material to the top inner margin of each corresponding web of corrugated material, thus closing the inner openings of the corrugated material; turning both web assemblies to a vertical position; filling the flutes of the corrugation of each web assembly with a commodity; adhesively treating the top inner margins of the flat wrapper material; folding, pressing and securing the top margin of each web of the flat wrapper material to the top inner margin of each corresponding web of corrugated material; thus closing the openings of each web of corrugated material; and transversely severing the webs to provide individual commodity units.
- 10 2. The method of making filled commodity container units by a sequence of operations; consisting in advancing a web of wrapper material having positioned lengthwise thereon and spaced apart from each other, and inward from the side margins of the wrapper web, two webs of single faced transversely corrugated flute formed material with the ends of the flutes open; severing the web of wrapper material to provide two web assemblies; adhesively treating the inner top margins of the wrapper material; folding, pressing and securing the inner margin of each web of wrapper material to the top inner margin of each corresponding web of corrugated flute formed material; turning both web assemblies to a vertical position; filling the flutes of the corrugation of each web assembly with a commodity; adhesively treating the top inner margin of the wrapper material; folding, pressing and sealing the top margin of each web of the wrapper material to the top inner margin of each corresponding web of corrugated flute formed material; and transversely severing the web to provide individual commodity container units.
- 15 3. The method of making filled wrapped packages by a sequence of operations; consisting in advancing a web of wrapper material having positioned longitudinally thereon two webs of flute formed material; severing the web of wrapper material to provide two web assemblies; folding, pressing and securing the inner margin of each web of wrapper material to the top inner margin of each corresponding web of flute formed material; filling the flutes of each web assembly with a commodity; folding, pressing and securing the unsecured margin of each web of the wrapper material to the open end margin of each corresponding web of flute formed material; and

transversely severing the web to provide individual commodity units.

4. The method of making filled wrapped packages; consisting in advancing a web of wrapper material and two webs of flute formed material; severing the web of wrapper material to provide two web assemblies; folding, pressing and securing one margin of each web of wrapper material to a margin of each corresponding web of flute formed material; filling the flutes of each web assembly; folding, pressing and securing the unattached margin of each web of wrapper material to the open end margin of each corresponding web of flute formed material, and transversely severing the web.

5. A machine for making filled, wrapped packages; comprising means to advance a web of wrapper material having positioned thereon two webs of flute formed material; a cutting knife to slit the wrapper material to provide two web assemblies; support for the web assemblies as they advance; means for applying a coat of adhesive to the top inner margins of the wrapper

5
10

material, mechanism to fold and secure the adhesively treated margins of wrapper material to the top inner margins of the flute formed material; mechanism to advance the web assemblies; means to turn the web assemblies; a device to fill the flutes as the web assemblies are advanced; mechanism to apply adhesive and fold the top margins of each wrapper web against the top inner margin of each flute formed web; means to advance each web assembly, mechanism to cut the filled flute formed web assemblies to provide individual, filled, wrapped packages.
